UNITED STATES PATENT OFFICE.

DANA S. KNOX, OF DENVER, COLORADO.

SIGNAL ATTACHMENT FOR LINOTYPE-MACHINES.

No. 884,934.

Specification of Letters Patent.

Patented April 14, 1908.

Application filed May 14, 1906. Serial No. 316,675.

To all whom it may concern:

Be it known that I, DANA S. KNOX, a citizen of the United States, residing in the city and county of Denver and State of Colorado, 5 have invented certain new and useful Improvements in Signal Attachments for Linotype-Machines; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 My invention relates to improvements in signal or alarm attachments for linotype machines and it consists of a neat, small, easily attached, cheap and efficient device for attracting the operator's or attendant's 20 attention when the molten metal in a linotype metal pot has reached a certain point where it should be replenished. I provide means of giving such signal during each cast of a line, a period of three seconds, and at no 25 other time, thus doing away with the annoyance of a continuous signal and the danger of the circuit being closed by the shrinking of the metal while cooling or other outside interference.

30 My construction includes a float composed of non-combustible material which protrudes into the metal pot and controls a lever which when the pot contains a sufficient amount of metal, is held in such a position that no signal is given. When, however, the metal is diminished or reduced to a predetermined level, the float acting on the lever throws its 35 free extremity into position to engage an electrical contact and close a circuit in which a signal or alarm device is located. The construction is such, however, that this signal can only be given when the pot swings forwardly to the casting position. Hence the signal when given is only instantaneous, and 40 as the operation continues the signal will be intermittent. This prevents a continuous alarm and it also prevents the possibility of closing the circuit except when the machine is in operation, since when the pot is in its 45 normal position the lever is not in position to engage the contact and close the circuit.

50 It is not desirable that a signal shall be given when the machine is not in operation even though the metal in the pot for some reason 55 should be sufficiently reduced to throw the lever into such position that when the pot

moves forwardly to the casting position, the circuit will be closed.

Having briefly outlined my improved construction as well as the function it is intended 60 to perform, I will proceed to describe the same in detail reference being made to the accompanying drawing in which is illustrated an embodiment thereof.

In this drawing, Figure 1 is a sectional 65 view taken through a linotype metal pot equipped with my improvements and shown in suitable proximity to an electrical contact for closing a signaling circuit. Fig. 2 is a detail view of the contact lever and its 70 actuating float. Fig. 3 is a top plan view of the same. Fig. 4 is a diagrammatic view illustrating means for producing signals or the alarms by virtue of my improvement, where a number of linotype machines are 75 employed. Each machine has its own individual circuit and signaling device though all the circuits are supplied from the same electrical source.

The same reference characters indicate 80 the same parts in all the views.

Let the numeral 5 designate a linotype pot of ordinary construction. In this pot the piston for pumping the molten metal during the operation of casting a line is 85 designated 6 and the piston rod 7. My improvement has nothing to do with these features of the construction. This pot, however, is provided with a downwardly extending arm 8 which engages a pin 9 which 90 forms a support upon which the pot swings during the ordinary operation of the device. That is to say every time a line is cast the pot swings forwardly or toward the right referring to Fig. 1 and, when it reaches a 95 predetermined position the molten metal is forced out through the passage 10 and the line casting act is performed. I take advantage of this movement of the pot to produce signals only when the pot is in its 100 forward position. Hence any signal is only instantaneous.

Upon the top of the pot is mounted a short post 12 upon which is fulcrumed a lever 13 by means of a fulcrumed pin 14 105 which passes through registering openings formed in the post and lever. The short arm 15 of this lever is a circuit-closing arm and is adapted to engage a contact 16 forming a part of the signaling circuit in which 110 is located a signal bell 17. The opposite or long arm 15^a of the lever is pivotally con-

2

nected with a rod 18 to whose lower extremity is attached a float 19 which protrudes into the chamber of the pot and rises and falls as the level of the metal fluctuates therein. When the quantity of metal in the pot is sufficient, the position of the float is such that the free extremity of the circuit-closing lever follows the course of the dotted line B in Fig. 1 and does not engage the contact 16 of the electrical circuit. When, however, the metal is sufficiently low to cause the float to fall or move downwardly a short distance, the arm 15 of the lever is raised sufficiently to cause it to engage the contact 16 when the pot moves forwardly to the casting position. The operator or person in charge of the apparatus is thus warned that a new supply of metal is required. It is of course important that this should be attended to before the metal gets so low that there is not enough within the pot to melt the pigs or slugs which are thrown into the pot in solid form, in which event it would be necessary to stop the machine until the fresh supply could be melted. By virtue of my signaling apparatus the metal is never allowed to get so low but that an additional pig or supply of cold metal may be thrown in and the operation continued since the body of the molten metal will be such as to melt the cold metal without interference or delay in the operation of the machine.

The float 19 is preferably composed of carbon which is at once buoyant, and not affected by the heat. Moreover the metal will not adhere to it.

In my improved construction I place all parts entirely out of the way, yet where they can be seen or reached or removed entirely even while the machine is running.

In forming the attachment between the float rod 18 and the lever, I employ a spring 20 having one extremity attached to the lever while a pin 21 is attached to its opposite extremity and passes through registering openings formed in the upper extremity of the rod and the adjacent end of the lever. This is a convenient and satisfactory way of forming the connection between the float and the lever though it is evident that any suitable means may be employed and would be operative.

Referring to Fig. 4 let the numeral 22 designate a source of electricity from the opposite poles of which lead wires or conductors 23 and 24. In this view three signal bells 17 are employed. Each of these bells or signaling devices is connected with the conductor 23 at a binding post 25. The conductor 23 leads directly to the bell farthest to the left

in this figure, while branch wires 26 and 27 lead to the binding posts 25 of the other bells. The conductor 24 is connected with all the levers 13 of my improvement by means of suitable connections. As shown in the drawing the lever farthest to the left is connected directly with this conductor while branch conductors 28 and 29 lead to the other levers 13. By virtue of this arrangement the circuit will be closed by a lever 13 connected with any linotype machine, as soon as the metal has become sufficiently lowered in the pot to actuate the lever as heretofore explained. The signal, however, will only be given at the machine in which the metal is low since in all the other machines the levers remaining in their normal position will not close the circuit as the pot moves forwardly to the casting position.

Attention is called to the fact that the long arm 15^a of the lever 13 with which the float is connected, is heavier than the opposite arm 15 and therefore the tendency of the float is to move downwardly. Hence as the level of the metal becomes lower in the pot, the float will move downwardly and allow the long arm of the lever to move in a corresponding direction, thus throwing the short arm 15 of the lever upwardly and when this movement is sufficient, the short arm 15 of the lever will engage the contact 16 when the pot is moved forwardly to the casting position, thus giving the signal and notifying the operator that the metal is low in the pot.

While I have shown and described electrical signaling mechanism, it must be understood that any suitable signaling device may be employed and is within the scope of the claims of the invention.

Having thus described my invention, what I claim is:

In a signal device for linotype machines, the combination with a receptacle for molten metal, of an alarm device independently mounted, a lever fulcrumed on the receptacle, a carbon float protruding into the molten metal of the receptacle and pivotally connected with one extremity of the lever to operate the same, the other extremity of the lever having an inclined contacting face which passes back and forth under the alarm when the receptacle has reached a predetermined point in its operating travel, said contacting face actuating the alarm in both directions of travel, substantially as described.

In testimony whereof I affix my signature in presence of two witnesses.

DANA S. KNOX.
